UNITED STATES PATENT OFFICE.

JACOB S. SCHAFF, OF DES PLAINES, ILLINOIS.

HEAD-REST ATTACHMENT.

SPECIFICATION forming part of Letters Patent No. 792,669, dated June 20, 1905.

Application filed August 18, 1904. Serial No. 221,242.

To all whom it may concern:

Be it known that I, JACOB S. SCHAFF, a citizen of the United States, residing at Des Plaines, in the county of Cook and State of Illinois, have invented certain new and useful Improvements in Head-Rest Attachments, of which the following is a specification.

This invention embodies a peculiar construction of head-rest and supporting means therefor, adapted especially to be used in connection with chairs or the like to afford a convenient support for the head.

The essential feature of the invention is to provide a head-rest attachment of the class described susceptible of various adjustments and of such a structure as to be readily secured to chairs of different styles when in use and comprising an arrangement of parts so mounted as to enable one to quickly disassemble such parts, so that they will occupy a minimum amount of space when the device is not in use.

For a full description of the invention and the merits thereof and also to acquire a knowledge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a perspective view showing the invention applied to a common type of car-chair at present in use. Fig. 2 shows the invention attached to a different style of chair. Fig. 3 is a front elevation of the head-rest and attachment therefor. Fig. 4 is a perspective view, parts broken away, showing the support for the head-rest, bringing out the exact construction thereof. Fig. 5 is a vertical sectional view taken on the line $\alpha\alpha$ of Fig. 3 looking in the direction of the arrow. Fig. 6 is a vertical sectional view through the head which secures the head-rest at the desired adjustment. Fig. 7 is a detail plan view, partially broken away, showing the means for attaching the head of the head-rest to the supporting member. Fig. 8 is a detail perspective

view of the head-rest, the adjustable head thereof being removed.

Corresponding and like parts are referred to in the following description and indicated in all the views of the drawings by the same reference characters.

The invention is specially advantageous for use in passenger-coaches of railways, being readily adapted for attachment to car-chairs, so as to form a convenient rest for the head of the passenger and relieve the jar and vibration usually incident to resting the head against the back of the chair in the ordinary manner.

Generally describing the same, the attachment consists principally of a support 1, adapted to be attached to a chair, a vertical adjustable supporting member 2, carried by the support 1, and the head-rest 3, adjustable upon the member 2 aforesaid. The support 1 is preferably of metal and may be of cast or other formation, as found most desirable, said support 1 being suitably backed by means of a pad 4, of fabric or like material, so that the attachment of the support to a larger or like part will not injure or damage the latter in any way. The support 1 is provided with vertical openings 5, the latter being formed in lugs 6, arranged at the upper and lower edge portions of said support. The openings 5, adjacent the ends of the support 1, receive vertical attaching-bars 7, the latter being provided at their upper end with engaging members in the form of hooks 8. The hooks 8 of the attaching-bars 7 are designed to engage over the upper portion of the back of a chair in supporting the attachment thereon, and the bars 7 are secured to the support 1 by means of set-screws 9, which are carried by the uppermost of the adjacent lugs 6 and which positively engage the said bar 7 in a manner readily apparent. The support 1 is vertically adjustable upon the bars 7, so that said support may be elevated or lowered at will in order to secure corresponding adjustment of the head-rest 3. In certain instances it is desirable to attach the support 1 by means of a strap 10 or the like, said strap 10 being passed through openings 11 in the support and adapted to pass about adjacent parts of the back of

a chair, as shown in Fig. 2 of the drawings. It will be understood that the strap 10 may be used with or without the hook-bars 7, since the strap is designed to support the attachment in either way.

The vertically-adjustable supporting member 2, mentioned above, which directly sustains the head-rest 3, consists of a vertical bar from which projects a horizontal arm 12, said 10 arm 12 carrying an adjustable head 13, to which the head-rest is secured. The head 13 is provided with a transverse opening 14, through which the arm 12 passes, and jam and clamp nuts 15 and 16 are threaded upon, 15 the end of the arm 12, so as to coöperate with the head 13 and properly position said head at an ascertained adjustment. The head 13 is rotatable upon the arm 12, and the nut 16 is adapted to be readily manipulated in order to 20 properly adjust the head-rest, as above described.

The head-rest 3 comprises a spring-frame 17, said frame being made, preferably, of spring-wire of suitable gage and removably 25 attached to the head 13. The frame 17 is composed of side bars 17^a, curved between their ends, and end bars 17^b. The side bars 17^a curve downwardly and toward each other, being secured at points intermediate their ends 30 to the head 13. The head 13 is provided with longitudinally-grooved portions 18, receiving the side bars 17^a of the frame 17, and said bars are prevented from displacement from the grooves 18 by means of a threaded rod, 35 19, which passes through the head in such a manner as to confine the bars 17^a in the grooves when the head-rest is in use, said rod 19 being readily removable, however, in order to admit of displacement of the frame 17, 40 from the head 13.

It will be understood that any suitable means may be utilized to secure the frame 17 to the head 13, and a hammock or flexible covering 20 is attached to the frame 17, so that the head may rest thereagainst. The covering 20 may be made from canvas or like material and secured to the frame 17 by any suitable attaching means, being stretched and carried by the end bars 17^b of said frame. The spring, 45 construction of the frame 17 forms a sort of cushion for the head when resting against the part 20, and this is extremely advantageous in that all vibration and jar, such as is usually common to the car-chairs during motion of the car, is absorbed with relief to the one using 50 the rest.

The member 2, which carries the head-rest 3, is supported by the part 1, and in order to vertically adjust this member the vertical bar 60 forming a part thereof is engaged by a clamp member 21, spaced from the upper portion of

the support 1 and preferably integral therewith. The clamp member 21 is adjustable by means of a set-screw 22, the set-screw passing through one end of the member 21 and screwing into the body of the support 1. Proper adjustment of the set-screw 22 will cause the member 21 to bind against or release the vertical bar of the member 2, so that a proper desired adjustment of said member 2 may be had. The head-rest 3 may be elevated or lowered by adjusting the member 2 relative to the support 1, and said head-rest may also be vertically adjusted by adjusting the support 1 upon the supporting-bars 7. Both of the above vertical adjustments may be utilized, if necessary.

From the foregoing it will be noted that the attachment may be readily mounted upon almost any style of chair now in use and may be used in connection with benches, seats, or like supports. The supporting member 2 is rotatable upon the support 1, so that the head-rest 3 may be reversed from one side to the other, the rotatable mounting of the head 13 being necessary in the above operation.

The construction of the attachment as above set forth is comparatively simple, and when it is desired to pack the attachment away out of use the supporting-bars 7 may be readily removed, the member 2 displaced, and the frame 17 disassembled or disconnected from its head 13, the latter being also adapted to be taken off of the arm 12 of the member 2. The various parts can then be packed in such a manner as to economize space, this being a practical feature of the invention.

Having thus described the invention, what is claimed as new is—

In a head-rest attachment, the combination of spaced supporting-bars provided with hooks at their upper ends, a support having vertical openings receiving the supporting-bars aforesaid, clamp-screws mounted upon said supports and adapted to engage the supporting-bars to fix the adjustment of the support relative thereto, a vertical supporting member adjustable vertically of the support and having a horizontal arm extended therefrom, a head adjustable upon the horizontal arm, jam and clamp nuts engaging the head to fix the adjustment thereof, and a head-rest removably attached to the head and comprising a spring-frame, said frame being provided with a flexible covering therefor.

In testimony, whereof I affix my signature in presence of two witnesses.

JACOB S. SCHAFF. [L. S.]
